Alfred Beck

UNITED STATES PATENT OFFICE.

ALFRED BECK, OF NEW YORK, N. Y.

SAFETY APPLIANCE.

1,148,820.

Specification of Letters Patent.

Patented Aug. 3, 1915.

Application filed January 14, 1915. Serial No. 2,126.

To all whom it may concern:

Be it known that I, ALFRED BECK, a subject of the German Emperor, residing at Queens borough, in the county of Queens 5 and State of New York, have invented certain new and useful Improvements in Safety Appliances, of which the following is a specification.

The present invention relates to safety appliances for windows and has for its object to provide a safety device for protecting a person against falling through an open window. In many houses, and particularly in the poorer sections of the city, the windows 15 often are very low, so that when open accidents frequently happen to women trying to hang out clothes or children playing near the window. Fixed railings or gratings arranged across the window are objectionable, 20 because they obstruct the light and hinder the cleaning of and repairs to the window.

To accomplish my object I provide a safety device which is so applied to the outside of the window frame, that at the opening 25 of the lower sash it will be automatically swung across the window opening, so as to form a safety railing or grating and on closing the window it will be lifted into a position in which it will not obstruct the 30 window.

To make my invention more clear, the same is illustrated in the accompanying drawing in which similar reference characters denote corresponding parts, and in 35 which—

Figure 1 is an outer perspective view of a window equipped with my safety appliance; Fig. 2 is a side view of the safety appliance and Fig. 3 is an elevation of a modified 40 form of construction of the safety device.

Referring specifically to the drawing *a*, *b* denote the sashes of the window which in ordinary manner are slidably arranged in the window frame *c*. At the lower end of 45 one of the counterweight casements of the window, a pinion *d* is arranged on a cross spindle *e* suitably borne in the window frame. The pinion *d* is adapted to slightly project through an opening *f* from within 50 the counterweight casement and to mesh with a rack section *g* fixed to the lower sash *b* of the window. The forward end of the spindle *e* projects outwardly from the window casement and has fixed to it an arm *m*. 55 Projecting from the outside of the window frame is a pin or pivot *i*, on which is

mounted a casting *j*. The latter is in form of a bell crank lever, of which one arm *j'* is bifurcated and the other *j''* is hollow, forming a cylindrical socket.

A link *h* is pivoted at one end of the arm *m* and at its opposite end is hinged to the bifurcated arm *j'*.

Engaging the socket of the arm *j''* is the lower cylindrical end of a rod *l* or the like and is securely held therein by a set screw *n*.

Fixed to the opposite side of the window frame in line with the fulcrum *i* of the casting *j* is a hook *o* or the like to receive the free end of the rod *l* when the latter is 70 swung into the dotted line horizontal position.

Normally, that is, when the lower sash is closed, the rod *l* occupies the vertical, full line position in which, it will be seen, it extends parallel to the lateral parts of the window frame and thus does not obstruct the window. When the sash is lifted, its rack *g* will transmit rotation to the pinion *d*, whereby through the medium of the arm *m*, link *h* and casting *j* the rod *l* will be 80 swung from its vertical into horizontal position forming a guard or safety railing.

Instead of using only a rod *l*, a grating *l'* (Fig. 3) may be fixed to the latter, so that 85 when in position of use it will cover a large area of the window opening.

To hold the rod or grating from vibrating a hook *p* projecting from the window frame engages the free end thereof, when in in- 90 operative position.

The arm *m* is fixed to the spindle *e* by a set screw *q* which enables the disconnection of the arm *m*, so that in case the appliance is not to be used, the rotation of the pinion 95 by the sash will not affect the safety railing.

It is, of course, understood that the construction of my device may be modified in various other ways without departing from the principle of my invention and I therefore do not wish to limit myself to the details described and shown.

What I claim and desire to secure by Letters Patent is:

1. The combination with a window frame 105 and window sash, of a safety appliance, comprising a member fulcrumed to the outside of the window frame and operatively connected to the window sash so that when the said sash is lifted to open the window 110 said member will be swung across the window opening to form a guard.

2. The combination with a window frame and window sash, of a safety appliance, comprising a member fulcrumed to the outside of the window frame, a pinion operatively connected to said member and borne in said window frame and a rack member on said sash adapted to mesh with said pinion, so that when lifting said sash the said member will be swung across the window opening to form a guard.
3. The combination with a window frame and window sash, of a safety appliance, comprising a member fulcrumed to the outside of the window frame, a pinion mounted in said frame, a motion transmitting mechanism between said pinion and member and a rack section on said sash to mesh with said pinion so that when lifting said sash the

said member will be swung across the window opening to form a guard.

4. The combination with a window frame and window sash, of a safety appliance, comprising a safety railing, a rotary member carrying said railing, a pinion in the window frame, motion transmitting means between said pinion and said rotary member and a rack section on the said sash to mesh with said pinion, so that when lifting said sash the said member will be swung across the window opening to form a guard.

In testimony whereof I affix my signature in the presence of two witnesses.

ALFRED BECK.
